CONSTRUCTION OF EVAPORATOR UNITS
AND COMPOSITE EVAPORATORS

Lewis M. Crosley and Roland H. Money, Cincinnati, Ohio, assignors to The Crosley Corporation, a corporation of Ohio

Application August 20, 1934, Serial No. 740,554

8 Claims. (CL. 62—126)

Our invention has to do with evaporators for mechanical refrigerators, and in particular with the construction of small sized evaporator units which combine cheapness with very high efficiency and very complete circulation. Such units may be used alone in the smallest sized refrigerators. It is possible to combine these units to make up larger evaporator structures for a variety of uses, including but without limitation, the refrigeration of liquids, cooling of air spaces, and the provision of evaporators for larger types of refrigerators. While it will be understood that the unit device of our invention is not restricted thereto, we shall describe it in an embodiment which was designed for use in a refrigerator cabinet having, say, two cubic feet of storage capacity, or thereabouts. Such refrigerators would usually be made with a cabinet of small size, in which a lower compartment houses the motor, compressor and condenser, and an upper or refrigerator compartment houses the evaporator, and has a lid swinging on horizontal pivots as distinguished from a door. The problems connected with the design of an evaporator for a structure of this type comprise considerations of size, smallness of vertical dimensions, efficiency in use, economy of construction, and sufficient capacity to permit its use with various types of refrigerant delivery means, especially the capillary tube and the like. The desideratum of relatively small, vertical dimensions suggests the use of an evaporator which is a good deal wider than it is deep, and this involves ancillary problems of the circulation of the refrigerant. Another problem is that of simplicity of design, combined with a construction which makes it possible to employ one or more ice cube trays and to freeze ice. The solution of these various problems embraces the primary objects of our invention, as respects the individual unit. As respects combination of our units, we shall describe another exemplary embodiment in which we attain a number of the objects referred to above, together with high efficiency, a better circulation and great economy as compared with any of the ordinary types of larger evaporators.

These and other objects which will be set forth hereinafter, or will be apparent to one skilled in the art upon reading these specifications, we accomplish by that certain arrangement of parts of which we shall now describe the aforesaid exemplary embodiment. For clearness reference is now made to the drawings, wherein Figure 1 is a plan view of our novel evaporator.

Figure 2 is a side view thereof, and

Figure 3 is a sectional view.

Figure 4 shows a refrigerator employing our evaporator.

Figure 5 is an elevational view of a larger refrigerator having a combination evaporator 5 which comprises a plurality of our units.

Figure 6 is a sectional view taken along the lines 6—6 of Figure 5.

Essentially in the practice of our invention, we provide a wide and relatively thin evaporator, 10 the main body components of which comprise three plates. An upper and a lower plate are pressed in dies so as to provide a header and an extension thereon, which extension is embossed with finger-like corrugations extending 15 nearly but not quite to the outer edge thereof. A pair of these plates may be placed in opposed relationship, with the third plate, which is a flat plate, between them. This flat plate serves as a diaphragm or division member between 20 upper and lower parts of the evaporator as such. It is perforated near its outer end so as to provide passageways from the lower embossed to the upper embossed portion, whereby the embossed portions are caused to act as continuous tubes. 25 I have shown in Fig. 1 an upper plate 1, having edge portions 2, lying substantially in the same plane. This plate is embossed as at 3 to form a longitudinally disposed header space, and is also embossed as at 4 to provide the finger-like 30 extensions as aforesaid. As shown in Fig. 2, the lower plate 5 is an embossed plate, essentially like the plate 1. While these plates may be made up as rights and lefts, it is more convenient to make them up from a single die. 35 When this is done, an orifice made at one end of the header and shown to the right at 6 in Fig. 2, will fall to the left as at 7 in the lower plate in the same figure. To the orifice 6 may be attached a fitting 8, to which will be connected in the usual way the outlet tube for gaseous refrigerant leading to the compressor. To this fitting I prefer to attach an oil skimming device indicated at 9, which is in the form of a tube, having, as viewed from above, a concave 40 bend therein and being open at the end marked 10 so as to form an inlet for refrigerant to be withdrawn through the fitting 8. The lowest portion of the orifice 10 will be above the tops of the embossed fingers 4. The purpose of the 45 skimming device 9 is to control the level of the refrigerant within the evaporator, and to assist in the removal of the oil which floats on the refrigerant. This oil collects in a sump formed by the concave bend in the tube 9, until sufficient 50

of it has accumulated to close off the sump, whereupon the oil is withdrawn as a slug through the fitting 8. The details of this oil skimming device do not form an essential part of our invention. They are more fully described in the copending application of Roland H. Money, one of the inventors herein, which has now matured into Patent No. 1,978,027 issued October 23, 1934.

To the orifice 7 there is attached a fitting 11, 10 to which may be connected whatever type of refrigerant delivery device is being employed. We prefer to use a capillary tube as a continuous refrigerant delivery device, but our invention is not limited thereto.

Between the plates 1 and 5 there is situated a third plate 12 shown both in Figs. 2 and 3. This plate is preferably of the same external dimensions as the plates 1 and 5, but is flat. Near its outer end, i. e. near the tips of the finger 4 it is perforated as shown at 13 in the figures, which perforations form the only connecting means between the two chambers into which the plate 12 divides the evaporator. The several plates are assembled in the relationship shown, and are welded together about their edges so as to make the evaporator tight. The plates may likewise be spot welded together between the fingers 4 if this is found desirable, in order to provide resistance to internal pressure. The evaporator may 30 afterward be tinned, or otherwise treated, as desired. The action of the device is as follows: Assuming that refrigerant in liquefied form is introduced into the device through the fitting 11, it first fills the lower header indicated at 14 35 in Fig. 2. Thence it flows outwardly toward the far edge of the device through the tube-like fingers 4 of the lower plate. It passes next through the perforations 13 in the tube-like fingers of the upper plate 1, and thence flows to 40 the header 3 thereof, whence it is withdrawn through the skimmer 9 and fitting 8. It will be understood that in the normal operation of the device, the refrigerant changes from liquid to gaseous form in the evaporator so that although 45 the evaporator is preferably of the flooded type and is kept full of liquid refrigerant to the level determined by the skimming device, the refrigerant as withdrawn therefrom is gaseous.

It will be seen that our device is exceedingly 50 simple and economical to construct. In spite of its relatively small dimensions it has a fairly high capacity, inasmuch as the lower header and a considerable portion of the upper header are kept full of refrigerant, as well as the tube-like portions. Embossed portions 4 form a continuous 55 passageway from one header to the other. Even circulation of the refrigerant throughout the evaporator is insured by these, and evenness of flow is further assisted by the fact that the inlet 60 and outlet fittings are respectively at opposite ends of the headers.

Such an evaporator may be supported in a refrigeration compartment in any way desired. We 65 have shown in the various figures the inner surface of a refrigeration compartment at 15, and various bracket members 16 serve as supports. These brackets may, if desired, be welded, or otherwise affixed to the evaporator as such, and detachably secured to the wall of the refrigeration 70 compartment, or the brackets may have such a construction that the evaporator may merely rest upon them by gravity. The former construction is perhaps preferable because the evaporator cannot then become displaced.

When supported as shown, the extension of the

evaporator beyond the headers forms a shelf upon which an ice cube tray of usual form and having the usual divisions, indicated at 17, may be placed. Likewise it will be possible to position an ice cube tray 18 underneath the shelf, but in close proximity thereto by a supplementary shelf, or the like, as shown at 18 in Figures 3 and 4. In mounting the evaporator it is well to give the shelf-like portion thereof a slight downward tilt to prevent the accumulation of moisture thereon.

In Figure 5 we have shown a larger refrigerator in which an evaporator of much greater capacity has been formed by joining together in series a plurality of the unit evaporators which we have hereinabove described. These units have been 15 broadly indicated in Figures 5 and 6, by the letters A, B and C, and will not be particularly described. It may be seen however, that it is possible to couple up our units in substantially any way desired, and when a number of units are 20 coupled together as in a refrigerator, the extensions of the unit evaporators not only may form the shelves upon which it is desirable to position ice cube trays, but also have the particular advantage that each tray then rests upon a refrigerator shelf. Consequently there is a much more 25 efficient heat interchange and a much more rapid cooling of the water in the trays. Moreover when a series of our units are combined as 30 aforesaid, the efficiency of the evaporator as such is increased by reason of the very positive circulation of refrigerant throughout all parts of the combination evaporator. Moreover our units, since they may individually be constructed very 35 cheaply, can be combined in a series giving evaporators of practically any total capacity desired, at a substantial saving in cost over unitary evaporators of the same capacity heretofore manufactured. As shown in the figures, the refrigeration is introduced through a tube 20 into the lowermost evaporator C, and the evaporators are 40 connected together in series by means of tubes 21 and 22. The refrigerant is withdrawn through the tube 23, which is connected to the oil skimming device hereinabove referred to. We have 45 shown ice cube trays 24 resting upon the shelf-like portions of the evaporator units A, B and C. We have shown these units connected together by suitable bracket members indicated at 25 and 26. These will not be particularly described inasmuch 50 as they may be varied for various types of refrigerators. It will be understood that a vertical arrangement of the units is not the only arrangement which may be chosen. Any number of the units may be connected together. A series of such 55 units so connected may likewise be connected in tandem where desired. The units lend themselves to various groupings which are particularly adapted to such uses as the cooling of refrigerated counters, liquid coolers and the like. In 60 the particular embodiments of Figures 5 and 6, we have shown a face plate 27 with openings therein to admit the trays, and having a cold control device indicated broadly at 28 mounted thereon. The capsule of the cold control device 65 may be mounted to the middle evaporator unit as at 29.

It will be obvious that by making the evaporator units with rights and lefts, or by making provision for openings at both ends of each heater, considerable lengths of the connecting tubing 21 and 22 may be eliminated, or in some instances the evaporators may be directly connected together as by welding or otherwise.

Modifications may be made in our invention without departing from the spirit thereof.

Having thus described our invention, what we claim as new and desire to secure by Letters Patent, is:

5. 1. An evaporator of substantially broad, flat shape comprising an enlarged portion at one side, and an extension therefrom lying substantially in a horizontal plane, said enlarged portion being 10 divided into upper and lower parts, and means within said evaporator for conducting refrigerant therefrom from one of the parts to the outer edge of said extension and back again to the other of said parts.
15. 2. An evaporator for refrigerators comprising an upper chamber and a lower chamber located in close proximity and having a relatively small combined vertical dimension, an extension from said chambers comprising an outward and return 20 path for refrigerant therebetween, said extension forming a shelf adapted to support an ice cube tray.
25. 3. A refrigerator evaporator comprising upper and lower embossed plates having upper and lower header members, and outlet and inlet means for refrigerant thereto, respectively, and an intermediate plate having at least one opening therein, all of said plates being fastened together and so arranged that the intermediate plate functions 30 to divide the headers from each other and to produce an even flow of refrigerant throughout said structure.
35. 4. An evaporator for refrigerators comprising upper and lower plates embossed to form headers and semi-tubular extensions therefrom, said plates being joined together to form an evaporator, and an intermediate baffle member formed to close off said headers and extensions from each other excepting in a restricted area for forcing 40 refrigerant introduced into one of said headers to traverse said extensions before it reaches the other of said headers.
45. 5. A broad and relatively flat evaporator comprising a portion adapted to form a shelf, said evaporator being divided internally by a diaphragm member, means for introducing refrigerant and withdrawing refrigerant from essentially the same side of said evaporator, said diaphragm being perforated to cause refrigerant 50 to traverse all internal parts of said evaporator between the inlet point and the outlet point, and said diaphragm serving otherwise to divide said inlet point from said outlet point.
6. A refrigerator evaporator structure comprising a plurality of units, each unit comprising upper and lower plates embossed to form a header upon one side and semi-tubular extensions therefrom, said plates being joined together in opposed positions with an intermediate baffle member therebetween, said baffle member serving to separate and close off the header formed in each 10 plate, to close off said semi-tubular extensions from each other, and to permit passage of liquid therebetween only at points therein remote from said headers for forcing refrigerant introduced into one of said headers to traverse said extensions before it reaches the other of said headers, said units being connected together in tandem, the upper header of one being connected to the lower header of the next and so on, the lower header of the first of said units being provided 20 with refrigerant inlet means, and the upper header of the last of said units being provided with refrigerant outlet means, said units being parallel and interspaced sufficiently to provide space for ice cube trays, whereby each unit forms a completely refrigerated shelf of a refrigerator evaporator.
7. An evaporator for refrigerators comprising a pair of embossed plates fastened together in opposed relationship, said plates being embossed to 25 form juxtaposed header portions and juxtaposed finger-like extensions which form tube-like portions, and an internal diaphragm completing the headers and perforated and arranged to cause refrigerant passing from one of said headers to 35 the other of said headers to traverse said tube-like portions.
8. An evaporator for refrigerators comprising a pair of embossed plates fastened together in opposed relationship, said plates being embossed to 40 form juxtaposed header portions and juxtaposed finger-like extensions which form tube-like portions, and an internal diaphragm completing the headers and perforated and arranged to cause refrigerant passing from one of said headers to 45 the other of said headers to traverse said tube-like portions, entrance means for liquid refrigerant adjacent one end of one of said headers and withdrawal means for gaseous refrigerant adjacent the other end of the other header.
